Patented June 24, 1919.

UNITED STATES PATENT OFFICE.

EDWARD T. MASSEY, OF NEW YORK, N. Y.

EMBLEMATIC BUTTON AND PROCESS OF MAKING IT.

1,307,870.

Specification of Letters Patent. Patented June 24, 1919.

Application filed November 5, 1918. Serial No. 261,215.

To all whom it may concern:

Be it known that I, EDWARD T. MASSEY, a citizen of the United States, residing at the city of New York, borough of Brooklyn, and 5 State of New York, have invented certain new and useful Improvements in Emblematic Buttons and Processes of Making Them, of which the following is a full, clear, and exact description.

10 My invention relates to buttons, particularly to emblematic buttons of the type provided with stick pins, and their method of manufacture. Primarily my object is to produce such buttons at less cost than those here- 15 tofore produced, while resembling the latter in appearance. I accomplish this object by employing an inexpensive readily deformable material, such as paper, for a backing sheet in which I embed the head and portion 20 of the shank of a straight pin, the deformable nature of the backing material holding the pin in place and obviating the necessity of providing the complicated structures for holding the stick pins in place 25 which are now in vogue. While I contemplate also using a facing sheet of inexpensive material, such as paper, I might, of course, use the pin-embedded backing sheets with the facings, now in use, which would mate- 30 rially reduce the expense of the present buttons, I have, however, discovered that by using both a facing of paper and a backing sheet of such material, I may simultaneously cut and unite the backing and facing sheets 35 and thus effect a very marked saving in the cost of producing the button. Hence I have described as my preferred form a button comprising both a backing and facing of paper.

40 The drawings accompanying this specification and forming part thereof illustrate one example of my invention.

Figure 1 is a perspective view of some of the elements and appurtenances used in carrying out my method;

Fig. 2 is a side elevation partly in section showing some of the elements and appurtenances in position to perform one of the operations;

50 Fig. 3 is a top plan view of one of the crown forming elements;

Fig. 4 is a side elevation partly in section of some of the elements and appurtenances employed in carrying out another operation;

55 Fig. 5 is an enlarged fragmentary vertical

section of the cutting dies employed in one of the operations with some of the elements to be operated upon in position;

Fig. 6 is a vertical section of my finished button, and

Fig. 7 is a vertical section similar to that shown in Fig. 5, but at right angles thereto.

Referring to the drawings, an anvil block 10 preferably of steel or iron is provided with a plurality of pin-receiving openings 11 60 adapted to receive pins 12, preferably geometrically arranged in rows in the block to facilitate the execution of some of the subsequent operations, as will hereinafter appear. Under each row of pin receiving openings 11, I provide a groove or chase 13 in the block 10, in which I place a strip of compressible material 14, such as rubber. Each of the compressible strips is faced with a thin strip of flexible metal 15. The strips of material 14 and facing strips 15 provide a yielding surface which permits the operation of bending the shank of the pins in the manner to be described, to be carried out without creating a hook on the end of the pin as 70 would be the case if the pin points rested on an unyielding surface. The rubber strips may be held in place in any convenient manner, as for example by a retaining plate 16. 75

The block 10 is further provided with a 80 pair of upstanding dowel or registry pins 17, which facilitate the proper positioning of the work with respect to the working elements. For each of the pin receiving open- 85 90

ings 11 there is provided on the upper surface of the block 10 a dome shaped former, which consists of a crowned disk of paper 18, (shown in Fig. 3), having a diametrical groove 19. These disks are located slightly eccentric to the pin receiving open- 95 90

ings 11, as shown in Fig. 1. A thin sheet of paper 20 is preferably pasted over these disks serving to retain them in place and forming a smooth surface for the assemblage of elements. The sheet, when applied, may 100 be thoroughly brushed, so that it will conform to the surface of the disks 18. I term this assemblage of block 10 and crowned disks a platen, and will so refer to it here- 105 after and in my claims.

In carrying out my method, I first prefer- 110 ably prepare a backing sheet 21, *i. e.*, the sheet which is to form the back of the button. This sheet may, and preferably does, consist of a fibrous material, such as a two-

ply sheet of paper. I either first perforate this sheet with perforations or holes 22 corresponding to the openings 11 and with registry openings 23, adapted to receive registry pins 17, or I indicate the proper position for openings 22 which can be made by stick pins 12 at the same time as they are positioned in openings 11 in a manner to be described. Assuming that the sheet 21 is 5 provided with perforations 22 and registry opening 23, and that it is in position on the block 10 with openings 23 engaging registry pins 17; stick pins 12 are positioned in openings 22 and 11 with their points bearing 10 on the resiliently-supported metallic strips 15. The heads and a portion of the shank of each pin project above the upper surface of sheet 21 in position to have the heads and the shank turned down and embedded 15 therein. To embed the pins in sheet 21, I utilize a pin-embedding device of any convenient construction, which may comprise a pressure roller as 25 under which the platen is adapted to move in the direction 20 of arrow A. The movement of the platen under the roller 25 bends down the heads of the pins and forces them and a portion of the shank of the pin into the backing sheet 21, the backing sheet being simultaneously 25 forced into radial openings 19 of disks 18 and partially crowned. The heads and a portion of the shank of pins 12 having been embedded in the backing sheet, a sheet of thin paper 26 having an adhesive 30 on both sides is united to the backing sheet 21 securely holding the heads and shanks of the pins 12 in position.

A facing sheet 28 of fibrous material, preferably of single-ply paper adapted to form the 40 face of the finished button is prepared by embossing or otherwise impressing therein a plurality of convexities, for instance, by means of male and female dies 30 and 31 shown in Fig. 4. The faces of the dies may 45 have any suitable configuration which will of course form a replica thereof in the convexities formed by the dies, and the sheet 28 may further be colored in any suitable manner. The convexities 33 shown in Fig. 50 are spaced and arranged relatively to each other in the same manner as the openings 11. As the convexities 33 are to form the face of the button, I provide registry openings, not shown, for the sheet 28, similar to 55 those provided for sheet 21, so that when the sheet 28 is placed on sheet 21 with the registry openings in position, the convexities 33 will be substantially centrally located with respect to the portion of the shank of 60 the pin embedded in sheet 21, that is, eccentric to the openings 11, and 22. The sheets are then ready for cutting and pressing.

A vertically reciprocating cutting member 65 having a plurality of cutting dies 36 having knife edges 37, wedge-shaped in cross

section, and a stem 39, is preferably employed to effect the cutting and pressing. The knife edges 37 are positioned concentrically with respect to the convexities 33 and on the upward movement of stem 39, cut the 70 sheet 28 and carry the edges of the cut portion over the edges of the cut portion of the sheet 21. The sheet 21 is only partially cut in this operation so that some of the subsequent operations may be more conveniently 75 carried out. In order that the cutting may be only partial, I provide a rubber disk 39a in each of the dies 36 and a rubber mat 40 having openings corresponding to the dies 36 on the cutting member 35 between these 80 dies. The sheet containing the partially severed buttons is then passed through a pin bending machine which bends the pins to their final position. The wedge-shape of the knife edges forces the edges of the facing sheet against the edges of the cut portion of the backing sheet and firmly unites them, and simultaneously carries the edges of the facing sheet over the edges of the backing sheet forming a smooth edge button. This button produced from two disks 85 of paper and a straight pin resembled the buttons heretofore produced from celluloid, metals, etc., and may be produced at a fraction 90 of their cost. 95

I claim:

1. The improvement in the art of making buttons which comprises embedding the head and portion of the shank of a pin in one face of a backing sheet, securing a facing sheet to said backing sheet to anchor said embedded head and shank portion therebetween against lateral displacement, cutting the button from said sheets, and bending over the remaining shank portion of the pin 100 along the other face of the backing material. 105

2. The improvement in the art of making buttons which comprises partially passing a pin through a sheet of fibrous material, bending the portion of the shank projecting above the surface downwardly and embedding the bent portion in said sheet to anchor the pin against lateral displacement, cutting a disk from said sheet, the pin having previously been passed through the disk before 110 being cut, and bending over the remaining shank portion of the pin along the other face of the backing material. 115

3. The improvement in the art of making buttons, which comprises partially passing a straight pin through a sheet of backing paper, bending the portion of the pin projecting above the surface of the paper downwardly, embedding the bent portion in the paper to anchor the pin against lateral displacement, covering the surface of the sheet in which the pins have been embedded with a facing sheet, cutting both sheets and simultaneously forcing the edges of the cut portion of the facing sheet over edges of the 120 125 130

cut portion of the backing sheet, and bending over the remaining portion of the pin along the other face of the backing paper.

4. A button comprising a backing sheet, 5 a pin extending through said backing sheet and having its head and a portion of its shank projecting above its surface bent downwardly and embedded in said sheet to anchor the pin against lateral displacement.
- 10 5. A button comprising a backing sheet having the head and a portion of the shank of a pin embedded in one face thereof, and a facing sheet secured to said backing sheet to anchor the pin against lateral displacement.

- 15 6. A button comprising a backing sheet, a pin having its head and a part of its shank embedded in one face of said backing sheet, and a sheet of facing material secured to 20 said backing sheet to anchor said embedded head and shank portion therebetween against lateral displacement, the remaining shank part of the shank being bent over

and extending along the other face of the backing sheet.

25 7. A button comprising a backing disk of paper having the head and a portion of the shank of a pin embedded therein, and a facing disk of paper having its edges covering the edges of the backing disk and united therewith to anchor the head and shank portion of the pin against lateral displacement.

30 8. A button comprising a backing disk of heavy paper having a pin passed eccentrically therethrough one end of said pin being 35 bent over and embedded in one face of said backing disk, and a facing disk of thin paper adhesively attached to said face of the backing disk to anchor the embedded portion of the pin against lateral displacement, the edges of the facing disk extending 40 down over the edge of the backing disk.

In witness whereof I subscribe my signature.

EDWARD T. MASSEY.
